SAWHORSE

James W. Cannon, 5714 Los Angeles,
Houston, Tex. 77026

Continuation-in-part of design application Ser. No.
2,932, July 5, 1966. This application Mar. 21,
1968, Ser. No. 11,085

Term of patent 14 years

U.S. Cl. D54—1
Int. Cl. D25—99

FIG. 1 is a plan view of a sawhorse showing my new design;

FIG. 2 is a bottom view thereof;

FIG. 3 is an end view thereof; the opposite end view appearing identical;

FIG. 4 is a side view thereof, the opposite side view appearing identical but that the opposite side of the latches would appear therein;

FIG. 5 is a bottom view thereof in folded position and turned sidewise to be hung on a wall; and

FIG. 6 is an enlarged, fragmentary isometric view of one end portion thereof.

The broken line disclosure of mounting pegs in FIG. 5 is for illustrative purposes only.

This application is a continuation-in-part of application Ser. No. D-2,932, filed July 5, 1966, and now abandoned.

I claim:

The ornamental design for a sawhorse, as shown and described.
